EARTH ANCHOR

Kenneth R. Way, Webster Groves, and Raymond N. Leach, St. Louis, Mo., assignors, by mesne assignments, to Jasper Blackburn Corporation, a corporation of Missouri

Filed Oct. 31, 1960, Ser. No. 66,223
3 Claims. (Cl. 189—90)

This invention relates to improvements in earth anchors for securing guy cables and the like, and has particular reference to an improved plate anchor.

The general object of the invention is to provide an improved anchor for guying heavy distribution and transmission structures, and one having great holding strength for its size and weight and which is relatively simple and inexpensive to manufacture.

Among the advantages of the present anchor are ease and facility of installation in either vertical or inclined machine bored holes, and a shape that conforms to the curved side surface of the hole so that it will quickly come into full surface pressure contact with the adjacent earth when tension is applied. These features obtain a reduction in creepage when the anchor is being set, and the elimination of spot loadings that tend to bend the anchor and impair its holding strength.

Other important advantages are an economical, waste-free use of the plate stock from which the anchor body is fabricated, and provisions that counteract the normal tendency of anchors, when installed in vertical holes, to ski or creep upwardly when load forces of great magnitude are applied.

A further important advantage of the present anchor is its tendency to remain stabilized in a normal position of optimum holding power and to resist forces that tend to unbalance and tilt it into a position of reduced holding power.

The foregoing and other objects and advantages are achieved in the provision of a dome-shaped anchor body formed in the present example from a square blank of plate steel. Surrounding the dome is an up-turned peripheral flange formed from the marginal portions of the metal blank. The corner portions of the blank remain on the finished product and are presented as upwardly and outwardly diverging points or flukes. A tie rod is detachably secured to the anchor body at the apex of the dome.

By reason of its rounded or bulbous shape the anchor is enabled to fit snugly against the side surface of a cylindrical hole drilled in the earth to receive the anchor. When installed in a hole that is drilled vertically, a growing practice in electrical pole line installations, the load forces which are initially applied to the anchor act immediately to bring the anchor into full surface pressure engagement with the adjacent soil. The flukes formed by the corner portions act to dig in and grip the undisturbed earth at the sides of the hole, preventing the anchor from side-slipping upwardly through the lesser resistant earth which has been replaced in the hole following installation of the anchor. The domed shape of the body and the relatively high point at which the rod is attached thereto favor stability and a retention of the anchor in its normal position of maximum holding power.

The foregoing and other objects and advantages of the invention will more clearly appear from the following detailed description of a preferred embodiment, particularly when considered in connection with the accompanying drawing, in which:

FIGS. 1 and 2 are phantom views showing the anchor of the present invention installed in a vertical bore in the earth;

2

FIG. 3 is a perspective view of the anchor;

FIG. 4 is a sectional view, and

FIG. 5 is a fragmentary view showing the underside of the central portion of the anchor body.

Referring now by numerals of reference to the drawings, the anchor hereof comprises a body part 10 and an anchor rod 11. The body part 10 is formed from a square blank of steel plate stock. The major portion of the blank, inwardly of its edges, is pressed to concavo-convex form, more particularly constituting the dome 12 which is preferably a spherical segment. The bottom periphery 13 of the dome 12 is circular in configuration. Its apex is provided with an opening 14 to accommodate the lower end of the anchor rod 11.

Formed integrally with the dome is the deep drawn rim or flange 15 which is inclined upwardly and outwardly. The flange 15 offers great resistance to failure from folding. It produces an annular trough or channel, V-shaped in cross-section, extending around the base of dome 12, which conduces to a solid packing of the earth in the said trough and at the upper surface of the anchor body.

The flange 15 includes the four corner portions of the original blank, the corners extending upwardly and outwardly from the bottom periphery 13 of spherical segment 12. They constitute flukes 16 for penetrating and gripping the earth at the sides of the bored hole, and otherwise serve to increase the anchor surface effective for resisting displacement.

A reinforcing plate 17 is welded to the underface of the apex portion of dome 12, and welded to the bottom of reinforcing plate 17 is a nut retainer 20 in which a nut 21 is fixedly held. As is best seen in FIG. 4, the nut 21 is retained in a position aligned with the rod opening 14 so as to engage threadedly the lower end of rod 11 extending through the apex of spherical segment 12.

The anchor is installed in a hole which, in accordance with modern practice, may be produced by a rotary drill. The bore is desirably inclined so as to be at a right angle to the guy cable but for reasons of ease and convenience anchor holes are frequently drilled vertically. The present anchor also lends itself to satisfactory installation in either slanting or vertical holes, especially because of its domed shape and anti-skiing provisions. In either arrangement a kerf 23 is cut in the ground laterally from one side edge 45 of the hole 22 to accommodate the anchor rod. Following proper placement of the anchor assembly in the aforesaid openings, the earth is replaced and tightly compacted about the anchor and rod.

The particular structure and formation of the dome 12 and the flange portion 15 provide an anchor of great strength and stability. Upon application of a tensional force on rod 11, such force is effectively resisted by the plate structure 10. The flukes 16 penetrate the earth at the sides of the hole and afford increased resistance to any tendencies of the anchor to move laterally, due, for example, to unequal density of the ambient material at different sides of the anchor. The rounded configuration of the dome portion makes for great strength and enables the body to fit closely against the cylindrical surface of the bored hole. In such position it can quickly assume full load when tension is applied, with minimum initial displacement or creepage.

It will appear that in the production of the anchor herein described there is practically no waste material. All portions of original blank, with the exception of the portion removed to form the central opening 14 for the anchor rod, are advantageously utilized.

Although the invention has been described by making detailed reference to a single preferred embodiment, such detail is to be understood in an instructive, rather than in any restrictive sense, many variants being possible within the scope of the claims hereunto appended.

We claim as our invention:

1. An earth anchor comprising a substantially square plate having corner portions, the square plate being formed to provide a rounded dome-shaped center portion and a flange portion extending upwardly from the bottom periphery of said center portion, the flange portion including upwardly projecting tapered flukes constituted by the corner portions of the square plate.

2. In an earth anchor a body formed from a square sheet metal plate having corner portions, said body comprising a rounded dome-shaped center portion, an annular flange projecting upwardly and outwardly from the bottom periphery of said center portion and constituting the outer wall of an annular trough, said flange including circumferentially spaced, upwardly projecting flukes constituted by the corner portions of the square plate, from which said anchor body is formed, and an anchor rod secured to said body at the apex of its dome-shaped central portion.

5

3. An earth anchor comprising a many-sided plate having corner portions, the plate including a rounded dome-shaped center portion, and an annular flange extending upwardly and outwardly from the bottom periphery of said center portion, said flange including circumferentially spaced, upwardly projecting flukes constituted by the corner portions of the many-sided plate.
